AUTOMOBILE LICENSE PLATE HOLDER

Gerald S. Rothman, New York, N. Y.

Application September 21, 1950, Serial No. 12,290

Term of patent 14 years

(Cl. D14—6)

To all whom it may concern:

Be it known that I, Gerald S. Rothman, a citizen of the United States, residing in New York city, in the county of Queens and State of New York, have invented a new, original, and ornamental Design for an Automobile License Plate Holder, of which the following is a specification, reference being had to the accompanying drawing, forming part thereof.

Fig. 1 is a front perspective view of an automobile license plate holder, showing my design,

Fig. 2 is a rear elevation view thereof, on a reduced scale, and

Fig. 3 is an exploded perspective front view of the automobile license plate holder shown in Figs. 1 and 2, on a reduced scale.

The dotted lines on the drawing, showing the printed matter, are shown for illustrative purposes only.

The transparent material bar element is

shaded on the drawing to show the contrasting appearance, between its linear gravings.

The drawing has been shaded to show contrasting appearance.

I claim:

The ornamental design for an automobile license plate holder, substantially as shown and described.

GERALD S. ROTHMAN.
